UNITED STATES PATENT OFFICE.

NORMAN WILLIAM MCLEAN AND WILLIAM ALEXANDER KYLE, OF PALMERSTON NORTH, NEW ZEALAND.

TEA MEASURING AND DELIVERING APPLIANCE.

Application filed May 21, 1923. Serial No. 640,541.

To all whom it may concern:

Be it known that we, NORMAN WILLIAM MCLEAN and WILLIAM ALEXANDER KYLE, subjects of the King of Great Britain, residing at 31 Lombard Street, Palmerston North, Dominion of New Zealand, and corner Ferguson and Cook Streets, Palmerston North, Dominion of New Zealand, respectively, have invented new and useful Improvements in Tea Measuring and Delivering Appliances, of which the following is a specification.

This invention relates to an appliance designed for use in measuring out and delivering small quantities of tea. The appliance is useful in private homes, tea rooms, restaurants and other eating houses, in which tea is brewed and served in tea pots, and is adapted by its construction to deliver a measured quantity of tea into a tea pot at each operation, such quantity being gauged as the amount requisite for each cup of the beverage to be made. The employment of the appliance therefore in making tea will serve to provide for the correct gauging of the strength of the tea and will also serve to prevent any waste by the use of excess quantities.

The appliance designed provides for the tea being placed within a transparent holder and for such holder then being placed, mouth downward, in a special frame so that the mouth fits into a tubular neck and the outlet of the mouth is blocked by a ball mounted to rotate within such neck and formed in its periphery with a cavity of a capacity equal to the quantity to be delivered on each operation. This cavity is disposed in the circumferential line of the ball's rotation so that it passes across the mouth of the holder and is thereby filled with tea and then passes round and spills its contents through the bottom of the neck.

The special construction of the device forming the invention is illustrated in the accompanying drawings, in which:

Figure 1 is a front elevation, and

Figure 2 is a side elevation thereof.

Figure 3 is a sectional front elevation of the delivery control portion of the appliance.

Figure 4 is a plan of the ball controlling the delivery.

In carrying out the invention a face board A is provided upon which to mount the appliance, this board being adapted to hang vertically against a wall or other fixture. A tubular fitting B is fastened to the front of the board at its lower end, and extends vertically and is disposed so that it stands out away from the board by being fixed to a bracket support C. The tube therefore forms a neck and has its bottom end made to taper inwards into spout form as at B'.

Fitted into the tube B is a ball D, of wood or other approved material, made of a diameter so as to form a neat fit across the passage through the neck and to rotate freely. This ball is fixed upon a spindle E passing diametrically through it and extending at both ends through bearings b formed in the tube B, on the respective sides. This spindle thus extends horizontally and transversely through the tube, and one end is bent into a crank handle, as at E', so that the spindle and ball may be rotated.

The peripheral surface of the ball is formed with a cavity F made therein at a point in the line of the ball's rotation. This cavity is made of a capacity to accord with the measure of tea to be delivered on each operation, and in the rotation of the ball therefore it first opens upwards in the tube and then downwards to its bottom.

The tea holder is formed by a bottle shaped vessel G, made preferably of transparent glass so that its contents may be viewed, having a mouth or neck G' of such a diameter as to be adapted to fit easily into the top of the tube B, when the holder is inverted, and for its mouth then resting upon the ball D so as to be sealed thereby. The body portion of the holder is encircled by a metal band H that is clamped around it at a point near its top, when in the inverted position in which the appliance is shown. This band is connected to the face plate A by means of cranked wire arms J disposed one on each side and journaled in the plate A and then hooked through eyes h on the respective sides of the band. This arrangement serves to retain the holder G in the vertical position when its neck is resting upon the ball D, as shown by the full lines in Figure 2, but will allow of the hold-

er being lifted so that its mouth may clear the top edge of the tube B, as shown by the dotted lines in Figure 2, and then to have such mouth swung out clear of the tube.

5 This special manner of mounting is to provide facility for charging the holder, which is done by taking down the appliance, swinging the holder mouth out from the tube and inverting the whole apparatus so 10 that the tea leaves may be poured into the holder. Then when it has been charged, the mouth is turned back into the tube and the appliance turned up again, when the mouth will rest upon and be sealed by the ball. 15 The appliance is hung upon its fixture in this condition and may then be used to deliver its measured quantities of leaves, as required, by giving the ball a rotation for each 20 measure wanted. As the cavity F opens upwards into the holder mouth it will be filled by the matter in the holder settling down, and this quantity will be carried round in the cavity and dropped through the spout B' into any receptacle placed below to receive it.

If desired, the bottom of the cavity F may be packed with a quantity of lead / that will serve to so dispose the ball's centre of gravity that when the ball is released 30 it will normally turn to the position at which the cavity opens downwards and thereby to keep the holder mouth covered.

We claim:—

1. A measuring and delivering appliance comprising a frame, a tubular neck secured 35 to extend vertically on the front of said frame, a ball fitted to rotate on a horizontal axis within said tubular neck and having a cavity formed in its peripheral surface in the line of its rotation, a holder for the material to be measured having a mouth 40 adapted to enter the top of said neck and be supported on the ball to form a closure for the holder, and means for connecting the upper end of said holder with the frame. 45

2. A measuring and delivering appliance comprising a frame, a tubular neck secured to extend vertically on the front of said frame, a ball valve mounted to rotate on a horizontal axis within said neck and having 50 a cavity formed in its peripheral surface on the line of its rotation, a holder for the material to be measured formed with a mouth adapted to extend downwardly and to enter within said neck and be supported on the ball to form a closure for the holder, a band 55 encircling the upper end of said holder, and cranked arms pivoted on said frame and linked to the encircling band, one on each side thereof.

In testimony whereof, we affix our signatures.

NORMAN WILLIAM McLEAN.
WILLIAM ALEXANDER KYLE.
